Atty.

UNITED STATES PATENT OFFICE.

HAROLD G. ESSAYAN, OF BROOKLINE, MASSACHUSETTS.

DESIGN FOR AN EMBLEM.

51,635.

Specification for Design.

Patented Jan. 1, 1918.

Application filed October 31, 1917. Serial No. 199,590. Term of patent 7 years.

To all whom it may concern:

Be it known that I, HAROLD G. ESSAYAN, a citizen of the United States, residing at Brookline, in the county of Norfolk and Commonwealth of Massachusetts, have invented a new, original, and ornamental Design for Emblems, of which the following is a specification, reference being had to the

accompanying drawing, forming part hereof in which—

The figure is a front elevation of an emblem showing my new design.

I claim—

The ornamental design for an emblem as shown.

HAROLD G. ESSAYAN.
